US00D346662S

United States Patent [19]

Larsen et al.

[11] Patent Number: Des. 346,662

[45] Date of Patent: ** May 3, 1994

[54] **COMBINED STACKED TEMPERATURE REGULATOR, POWER SUPPLY AND GEL DRYER FOR ELECTROPHORESIS**

[75] Inventors: **Duke Larsen, Lake Geneva; Robert W. Dunst, Cedarburg; Timothy G. J. Ehr, Menomonee Falls; Stephen H. Gorski, Wauwatosa; Michael E. Hansen; Brian P. Walsh, both of Pewaukee, all of Wis.**

[73] Assignee: **Fotodyne Incorporated, Hartland, Wis.**

[**] Term: **14 Years**

[21] Appl. No.: **820,391**

[22] Filed: **Jan. 14, 1992**

[52] U.S. Cl. **D24/233**

[58] Field of Search ..... **165/104; 204/299 R, 204/182.8; D24/233**

CLAIM

The ornamental design for a combined stacked temperature regulator, power supply and gel dryer for electrophoresis, as shown and described.

DESCRIPTION

FIG. 1 is a perspective view showing our new design; FIG. 2 is a front elevational view; FIG. 3 is a side elevational view, the opposite side elevational view being a mirror image thereof; FIG. 4 is a top plan view; FIG. 5 is a reduced rear elevational view; and, FIG. 6 is a reduced bottom plan view.
